UNITED STATES PATENT OFFICE.

BENJAMIN DAY, OF WEST HOBOKEN, NEW JERSEY.

DESIGN FOR A PRINTING-FILM.

SPECIFICATION forming part of Design No. 33,707, dated December 11, 1900.

Application filed November 2, 1900. Serial No. 36,299. Term of patent 14 years.

To all whom it may concern:

Be it known that I, BENJAMIN DAY, a citizen of the United States, and a resident of West Hoboken, in the county of Hudson and State of New Jersey, have invented and produced a new and original Design for a Printing-Film, of which the following is a full, clear, and exact specification.

My design consists in a printing-film having a series of dots arranged irregularly, as shown in the accompanying drawings, in which—

Figure 1 is a plan of a portion of the film, while Fig. 2 is the right-hand continuation

thereof, the line *a a* indicating the junction 15 of the two sections.

Having thus described my invention, I claim as new and desire to secure by Letters Patent—

The design for a printing-film, as herein 20 shown and described.

In testimony whereof I have signed my name to this specification in the presence of two subscribing witnesses.

BENJAMIN DAY.

Witnesses:

JOHN LOTKA,
EVERARD BOLTON MARSHALL.
